(57) **CLAIM**

We claim the ornamental design for a fan, as shown and described.

DESCRIPTION

FIG. 1 is a front perspective view of a fan in accordance with the invention.

FIG. 2 is a left-side view of the fan of FIG. 1.

FIG. 3 is a right-side view of the fan of FIG. 1.

FIG. 4 is a front view of the fan of FIG. 1.

FIG. 5 is a rear view of the fan of FIG. 1.

FIG. 6 is a top view of the fan of FIG. 1; and,

FIG. 7 is a bottom view of the fan of FIG. 1.

The portions of the fan shown in broken lines are included for the purpose of illustrating environment and form no part of the claimed design.
